(57) **CLAIM**

The ornamental design for lamp, as shown and described.

DESCRIPTION

FIG. 1 is a perspective view, from above right, of the lamp;
FIG. 2 is a perspective view, from below right, thereof;
FIG. 3 is a left side view thereof;
FIG. 4 is a right side view thereof;
FIG. 5 is a front view thereof;
FIG. 6 is a top view thereof; and,
FIG. 7 is a bottom view thereof.
The broken lines represent portions of the lamp which form no part of the claimed design.
